CLAIM

The ornamental design for a rollable stamp, as shown and described.

DESCRIPTION

FIG. 1 is a perspective view from the front, right, and top side of a rollable stamp showing my design;
FIG. 2 is a front elevational view thereof;
FIG. 3 is a rear elevational view thereof;
FIG. 4 is a left side elevational view thereof (the right view being identical thereof);
FIG. 5 is a top plan view thereof;
FIG. 6 is a bottom plan view thereof; and,
FIG. 7 is an exploded perspective view thereof in an unfolded condition.

FIG. 1

FIG. 7

FIG. 3

FIG. 2

FIG. 4

FIG. 6

FIG. 5
